UNITED STATES PATENT OFFICE.

LEON OTTINGER, OF NEW YORK, N. Y.

LATCH.

Application filed October 24, 1921. Serial No. 509,823.

To all whom it may concern:

Be it known that I, LEON OTTINGER, a citizen of the United States, and a resident of the city of New York, county and State of 5 New York, have invented a certain new and useful Improvement in Latches, of which the following is a specification.

This invention relates to latches and more particularly to latches for automobile doors, 10 such for instance as that shown in patents numbered 1,312,199 or 1,386,422, granted to me on August 5, 1919 and August 2, 1921, respectively.

Generically considered, it is the primary 15 object and purpose of my present improvement to simplify and increase the efficiency of the means for locking the latch disclosed in the patent last referred to whereby the owner of an automobile may lock the latches 20 of all doors except one from the interior and then lock the remaining door after he leaves the car from the exterior by means of a key-actuated lock.

In carrying out the present invention I 25 propose to provide means for locking the latch bolt retracting means against actuation which is rendered effective by means of a rectilinearly movable part.

More specifically, in one construction the 30 interior operating handle for the latch is mounted for rectilinear shifting movement. This handle is provided with means, which, when said handle is shifted in one direction, prevents the actuation of the latch bolt by 35 means of the exterior operating handle. At the same time, however, in certain constructions, which will hereinafter be fully described, in case the latch mechanism is thus locked while the door is opened, the bolt 40 may be repressed or freely forced back when the door is closed, thus obviating the possibility of injuring the latch or the door structure.

In certain contemplated embodiments of 45 the invention, I also provide means for imparting the rectilinear movement to the interior latch operating handle and for securely locking said handle against movement from its effective position wherein the latch 50 mechanism is locked against operation by the exterior handle. If desired, in one form of this locking means for the interior handle, means actuated from the exterior of the

door by a suitable key may be provided, and the interior handle thereby shifted from the 55 exterior of the door to release the latch mechanism for operation.

With the above and other objects in view, the present invention consists in the improved latch and in the form, construction 60 and relative arrangement of the parts in the several illustrated embodiments thereof as will be hereinafter more fully described, illustrated in the accompanying drawings and subsequently incorporated in the subjoined 65 claims.

In the drawings wherein I have disclosed several desirable embodiments of the invention and in which similar reference characters designate corresponding parts throughout the several views:

Figure 1 is an elevation of a latch of the type shown in my prior Patent No. 1,386,422 having one of the side plates of the latch casing removed, wherein I have illustrated 75 one embodiment of the present invention;

Figure 2 is a fragmentary elevation showing the interior latch operating lever raised to lock the interior and exterior operating handles; 80

Figure 3 is an elevation similar to Figure 1 showing an alternative form of the invention;

Figure 3^a, is a detail view showing an alternative form of the locking means shown 85 in Figure 3;

Figure 4 is a fragmentary elevation illustrating another modification;

Figure 5 is a similar view showing the interior operating lever raised from the position seen in Figure 4 to lock the latch bolt 90

Figure 6 is an enlarged detail elevation to more clearly illustrate the locking action;

Figure 7 is an exterior elevation of an 95 automobile car door illustrating the different angular positions of the interior lever handle visible through the glass window to serve as a means indicative of the locked or unlocked condition of the latch; 100

Figure 8 is an enlarged detail view showing the two positions of the interior lever and the lever provided with a positive indicating means visible in the locked position of the lever. 105

Figure 9 is a fragmentary elevation of

the latch illustrated in Figure 5 of Patent No. 1,386,422 and showing another form of the invention;

Figure 10 is a sectional view taken on the line 10—10 of Figure 9;

Figure 11 is a section taken on the line 11—11 of Figure 10;

Figures 12 and 13 are plan and perspective views respectively, illustrating another means which may be provided on the window sill of the car door for locking the latch actuating lever;

Figure 14 is a detail view showing another alternative construction which is particularly designed for use in connection with a rotatable latch actuating lever of the type shown in Figure 1 of Patent No. 1,312,199;

Figure 15 is a fragmentary elevation showing still another embodiment of the invention;

Figures 16 and 17 are detail views illustrating a further embodiment of the device;

Figure 18 is a detail vertical section showing a slight modification of the device illustrated in Figure 17;

Figure 19 is a detail elevation of still another embodiment of the invention;

Figures 20, 21 are detail views showing an exteriorly operated locking device for the interior latch actuating lever;

Referring in detail to the drawings and more particularly to Figures 1 and 2 thereof, in which I have illustrated a latch mechanism corresponding to that shown in my prior Patent No. 1,386,422, 10 designates the base plate upon which the several latch parts are mounted. The latch mechanism is secured in one side of the body of the door at a suitable distance below the window sill, and of course, outside of the runway in the door body into which the window is adapted to be lowered in the usual manner.

As disclosed in the patent referred to, the latch mechanism includes the spring projected latch bolt 11 which is mounted and guided at its rear end in an angular casting 12 fixed upon the base plate 10. This latch bolt at its outer end may be of any preferred form and construction for engagement with the striker on the door frame or jamb, but I preferably provide the projecting end of the latch bolt with an automatically acting expanding means similar to that shown in my prior Patent No. 1,312,199.

The bolt 11 carries an upwardly projecting laterally curved arm 13 with which the end of a roll-back lever 14 is adapted to engage. To the roll-back 15 of this lever, which is rotatably mounted in the plate 10 and the casting 12, the shank of an exterior latch operating handle is suitably fixed.

The latch bolt 11 may also be retracted from the interior of the car or vehicle by

means of a lever 16 which has bearing engagement against an upwardly projecting lug 17 on the latch bolt 11. This interior operating lever for the latch will presently be more particularly referred to.

To the roll-back lever 14 one end of a rod 18 is pivotally connected, said rod at its other end being freely movable through a guide opening in the upwardly projecting lug 19 on the casting 12.

A spring 20 surrounding said rod acts to yieldingly hold the roll-back lever against the angular flange 21 on one end of the base plate 10 when the latch bolt is not fully projected, and thereby prevents rattling of the lever. All of the parts above described are similar to those shown in my prior Patent No. 1,386,422 to which reference may be had for a more detailed explanation of the operation of the latch mechanism. The interior operating lever 16 for the latch extends between the base plate 10 and the latch bolt 11 and the lower portion of this lever is laterally curved as shown at 22. At its lower extremity said lever is provided with a short longitudinally extending slot 23, a notch 24 being formed at each end of said slot and communicating with one side thereof. Through the slot 23 a stud bolt 25 fixed in the base plate 10 extends. It will thus be understood that the lever 16 may be vertically or rectilinearly shifted, such movement of the lever being limited by the stud 25 engaging the opposite ends of the slot 23.

The lever 16 extends upwardly through a slot provided in the window sill and may be provided with an upper adjustable section 26 which can be adjusted and fixed in any required position in accordance with the location of the latch in the door body so that the operating handle 27 fixed to the upper end of the lever will be above the window sill and visible through the glass pane. One edge of the lever 16 is provided with a lug in which a transversely disposed locking pin 28 is fixed, said pin projecting from opposite sides of the lug. One end of this pin is movable in a horizontal slot 29 formed in the base plate 10 in the operating movement of the lever. At one of its ends this slot is provided with an upward extension 30. When the lever 16 is in the position seen in Figure 1 of the drawings, the latch bolt 11 may be retracted from its projected position either by the operation of the roll-back 14 by means of the exterior handle or by the operation of the inside lever 16. This operating movement of the lever 16 is yieldingly resisted by the spring pressed pin 31 mounted in the lower end of the casting 12, said pin bearing against one edge of the curved lower end of the lever and operating to yieldingly hold the notched or recessed upper end of the slot 23 in engagement with

the guide stud 25. In the movement of the upper end of said lever to the right from the position shown in Fig. 1, said lever pivots upon the stud bolt 25 and bearing against the lug 17 retracts the latch bolt 11 so that the door may be opened. When it is desired to lock the door in closed position upon leaving the car, the lever 16 is pulled upwardly from the position shown in Figure 1 until the pivot stud 25 seats in the notch 24 at the lower end of the slot 23. One end of the locking pin 28 will then be positioned in the upward extension 30 of the slot 29, while the other end of said pin will be disposed in the path of movement of the rod 18. Thus, the lever 16 is locked against pivotal movement, while the roll-back lever 14 to which rod 18 is connected is likewise locked against movement by the actuation of the exterior operating handle. It will, therefore, be understood that each door equipped with the improved locking means is securely locked against the possibility of the same being opened from the exterior of the vehicle. This locking action may be very quickly effected through a simple rectilinear shifting movement of the interior operating lever.

When the lever 16 is in its unlocked position, the upper end of the lever and the operating handle visible through the window pane of the door, stands perpendicular. Owing to the curvature of the lower end of the lever, when said lever is raised to its locking position, the upper end thereof is disposed at an angle from the perpendicular as seen in Figures 8 and 9 of the drawings. This affords an indication to the owner of the car so that he may ascertain at a glance whether or not the door is locked, so that, if locked, he will not attempt to actuate the latch by means of the exterior operating handle. As shown in Figure 8, if desired, the upper end portion of the lever 16 may also have embossed or otherwise delineated thereon the word "Locked" as indicated at 32. When the lever is in its unlocked position, this word is disposed below the upper edge of the window sill and is invisible, but when the lever is raised to its locked position, is disposed above the door sill and may be readily observed.

In Figure 3 of the drawings I have shown another form of the invention wherein the interior lever 16' is mounted and arranged in the manner above described and is provided in one of its edges with a notch or recess 33. One end of a locking lever 34, fulcrumed intermediate of its ends, as at 35, is engaged in this recess. A suitable spring 36 coacts with this lever at one side of its pivot to normally hold the same in the position shown in full lines in Figure 3, in which position the roll-back lever 14 may be operated by means of the exterior handle to retract the latch bolt. In the return of the

lever 16 to its normal position after the latch bolt has been retracted thereby, the end of the locking lever 34 is received in the recess 33. When it is desired to lock the latch, the interior lever 16' is pulled upwardly, thereby moving the locking lever 34 to the position shown in dotted lines in the drawing so that the other end of this lever is positioned in the path of movement of the upper end of the roll-back lever 14. Thus retraction of the latch bolt from its projected position by means of the exterior operating handle is prevented. It will be apparent that when an attempt is made to thus retract the bolt by the exterior handle, the roll-back lever 14 will tend to rock the lever 34 on its pivot 35 and there will be no pressure transmitted through this lever to the interior operating lever 16' such as would tend to rock the lever on its pivot 25 and retract the bolt. Therefore in this construction it is not necessary to use the locking means for the lever 16' as shown in Figures 1 and 2 of the drawings.

In Figure 3^a of the drawings, I have shown another alternative, wherein the locking means is actuated automatically upon the movement of the inside lever to its normal position to lock the latch mechanism, while said means is manually operated independently of the inside lever to unlock the mechanism. As shown, the lever 34^a is pivoted at one end as at 35^a, the other or free end of said lever being angularly offset to extend across the inside operating lever 16^b and downwardly curved as at 42. In this case the lever 34^a also carries a pin 37' moving in the slot 38'. In the lever 16^b a stud 43 is fixed, and in the movement of the lever 16^b to its normal position this stud engages the upper face of the curved end 42 of the lever 34^a when said lever is in the raised position and by camming action forces said end of the lever downwardly, thereby moving the pin 37' into the lower end of the slot 38 behind the roll-back lever 14. The curved end 42 of the lever 34^a in the side thereof opposed to the lever 16^b is provided with a vertical recess or groove 44 and said end of the lever 34^a between the groove 44 and the extremity of the lever also has its lower portion cut away or recessed as indicated at 45. Thus when it is desired to release the latch mechanism for operation, the pin 37' is manually shifted into the upper end of the slot 38', thereby raising said lever until its curved end is positioned above the pin 43.

In the recess 45 in the curved end 42 of the lever 34^a, a dog 46 is pivoted at one of its ends. When the lever 16^b is pivotally moved from its normal position to operate the latch mechanism, with the lever 34^a in the raised position, the pin 43 on said lever lifts the dog 46 so that said pin may pass through 130

the recess 45. After passing beyond said recess the dog 46 drops by gravity to its normal position and closes the outer side of said recess so that in the return movement of the 5 lever 16^b the pin 43 will ride over the end of said dog and upon the upper edge of the lever 34^a, thereby automatically moving the lever downwardly to dispose the pin 37' in its locking position with relation to the roll- 10 back lever 14. In this construction, it will be seen that the automatic locking action is produced in a pivotal movement of the interior operating lever so that the lever is not mounted for vertical shifting movement as 15 in the embodiments of the invention previously described.

In Figures 4, 5 and 6, I show an adaptation of my present improvements whereby a more direct locking action is obtained between the interior operating lever and the latch bolt. In this case the lower edge of the latch bolt 11 is provided with a notch or recess 47, one end wall of which is beveled or undercut as at 48 while the base wall 49 of 20 said recess is inclined upwardly from said end wall 48 to the opposite end wall of the recess. The interior operating lever 16^c which is mounted for vertical shifting movement as above explained, carries a locking 25 stud or pin 50. When the lever 16^b is in its normal operating position as seen in Figure 4, the locking pin 50 is disposed below the lower edge of the latch bolt 11, thereby permitting of the free retraction of said bolt 30 by either the interior or exterior operating handles. When the lever 16^b is pulled upwardly with the latch bolt in its normal position, the pin 50 moves into the recess 47 and into contact with the inclined base wall 35 49 of said recess. Any attempt to retract the latch bolt by the operation of the exterior handle causes the undercut wall 48 to engage one side of the pin 50, thereby tending to force the same upwardly and further 40 increase the binding or locking engagement of the pin with the walls of said recess. Likewise, it will be evident that the lever 16^c is locked against a pivotal movement when in its raised position.

50 In Figures 9, 10 and 11 of the drawings, I have illustrated an adaptation of my present invention as applied to an interior retracting means for the latch bolt of the type shown in Figure 5 of my Patent No. 1,386,422. In 55 this arrangement, the interior operating handle 52 is suitably fixed to one end of the shaft 53 of a roll-back lever 54. This shaft is rotatably supported in the base plate and in a suitable bearing on the guide plate 55 60 which is spaced from the base plate and suitably secured thereon. Between these plates the spring held carriage 56 is slidably mounted and has a lug 57 coacting with a shoulder on the latch bolt in the manner 65 more fully described in my issued patent.

This carriage is provided with spaced parts, one of which is engaged by the roll-back lever 54 and the other by the roll-back lever 14' which is actuated by the exterior handle. The part of said carriage which is engaged 70 by the roll-back lever 54 is provided with an extension or yoke 58 which loosely embraces the lever 54.

The roll-back shaft 53 is also capable of an axial shifting movement in its bearings. 75 A coil spring 59 surrounds said shaft and has one of its ends fixed to the base plate and its other end secured to a collar 60 fixed on the shaft. This spring acts to yieldingly hold the operating handle 52 and the roll- 80 back lever 54 in normal position. This spring also resists the longitudinal shifting movement of the shaft 53 in one direction to hold the roll-back lever 54 in a recess 61 in the face of the base plate as clearly shown in 85 Figure 11, in which position of the roll-back lever it will be also noted that the end of the yoke extension 58 on the carriage 56 is engaged with one edge of said lever. Thus in this normal position of the parts when the 90 latch bolt is projected, it will be understood that the carriage 56 cannot be moved to retract the latch bolt by actuating the other roll-back lever 14' through the medium of the exterior operating handle. In order to 95 release the carriage 56 for operation, the inside lever 52 is forced towards the side of the car door and the shaft 53 shifted longitudinally in an inward direction, thus displacing the roll-back lever 54 from the recess 100 61. The shaft 53 may then be turned, the end of the roll-back lever moving freely in the yoke 58 and bearing against the carriage 56 to shift the same against the action of its holding spring and thereby retract or withdraw the latch bolt. Upon the return of the interior handle and the roll-back lever 105 54 to its normal position, the latch mechanism is again automatically locked against 110 operation.

In Figures 12 and 13, I have illustrated another means for locking the vertically shiftable interior latch operating lever in 115 its raised position. The lever is provided upon one of its edges with a transversely projecting rib 62 and adjacent one end of this rib, a horizontally extending lug 63 is formed on the lever. Upon the surface of the window sill of the car door surrounding the slot in which the latch operating lever 120 moves, a plate 64 is secured, said plate of course, likewise having a slot 65. In one edge of this slot adjacent one of its ends a notch 66 is provided. The lever bar is of less thickness than the width of the slot 65 125 and in the operating movement of said lever the lug 63 is disposed below said slot, the rib 62 engaging one edge of the slot while the lever is engaged against the opposite edge thereof. When the lever is in its normal 130

position, upon lifting the same to lock the latch mechanism as above explained, the lug 63 is positioned above the plane of the plate 64. The lever is then shifted transversely in the slot into contact with the inside edge thereof so that the rib 62 below the lug 63 is disposed in the notch 66 while the lug 63 is engaged upon the upper face of the plate 64 and acts as a stop preventing the downward movement of the lever.

In Figure 14 of the drawings I have shown another embodiment of the invention which is more particularly applicable to an interior latch operating means of the character disclosed in my prior Patent No. 1,312,199. In this case, instead of providing a pivotally movable interior operating lever, the latch bolt is actuated from the interior of the car by means of a rotatable vertically disposed rod extending upwardly above the window sill of the door. As shown in Figure 14, this operating rod 67 is provided on its lower end with an operating cam 68 which engages a lug or extension 69 on the upper side of the latch bolt. The upper end of the rod above the window sill is provided with a suitable horizontally disposed handle 70 for the convenient operation of the rod 67. The rotation of this rod to retract the latch bolt is yieldingly resisted by means of the spring 71. Upon the rod 67 a sleeve 71' is loosely engaged and is provided at its lower end with a downwardly projecting finger 72 adapted to engage in a notch or recess 73 formed in the end of the rod 18' which is connected to the roll-back lever actuated by the exterior handle as above explained. A pin 74 is fixed in the sleeve 71 and is movable in a bayonet slot 75 provided in the rod 67. The sleeve 71 extends to the upper surface of the window sill, and between said upper end of the sleeve and the handle 70, a spring 76 surrounds said rod. This spring acts to force the sleeve 71 downwardly and normally hold the finger 72 in the recess 73 of the rod 18'. It will, therefore, be apparent that the rod 67 is thus held against operative rotation to retract the latch bolt while the rod 18' is held against movement, thus preventing retraction of the bolt by means of the exterior handle. When it is desired to operate the latch, the sleeve 71 is pulled upwardly and slightly rotated to engage the pin 74 in the horizontal portion of the slot 75, thus disengaging the finger 72 from the rod 18'. The latch bolt can now be retracted either by the operation of the exterior handle or by the rotation of the rod 67.

In the constructions to which I have above referred, a manual operation other than that incident to the ordinary operating movement of the latch actuating lever is necessary in order to lock the mechanism. In Figure 15, however, I have shown an embodiment of

my invention in which this locking action occurs automatically as the latch operating lever returns to its normal position in the projecting movement of the bolt. In this case, the interior lever 16^a is provided with the transversely disposed locking pin 28'. One end of this pin moves in a slot 29' provided in the base plate 10, said slot being slightly curved in accordance with the arc of operating movement of the lever. At its upper end this slot is provided with a cam portion 81. It will be understood that in this construction the lever 16^a is mounted at its lower end for vertical shifting movement in the manner shown in Figure 1 of the drawings excepting that the notches 24 are eliminated. Therefore, as the lever moves towards its normal position under pressure of the latch bolt as it is projected, the pin 28' when it enters the cam portion 81 of the slot 29' will cause said lever to move upwardly and thereby position the other end of the pin against the end of the rod 18 when said lever arrives at its normal position. The end of the cam portion 81 of the slot has a recess 82 at its lower side in which the pin 28' seats. Therefore, lateral pressure against said pin upon the attempt being made to operate the latch by the exterior handle will be ineffective to move said pin in the slot and shift the interior operating lever from its normal position.

In Figures 16 and 17 I have shown another means for retaining the latch operating lever in its locking position. In this construction the plate secured to the window sill is provided with an upstanding flange 83 having an angular slot 84 therein, one end 85 of which is enlarged and opens downwardly, while the other horizontally disposed end portion 86 of said slot is closed. In this case, the lever is constructed in two sections which are hingedly connected to each other as at 87. The upper section 16^a of the lever carries a pin 88 having a terminal head 89. When the lever is in its normal perpendicular position the pin 88 is in alignment with the open end 85 of the slot 84. The head 89 on said pin is of such diameter that it may pass through this enlarged end of the slot. Therefore, when the upper section 16^a of the lever is shifted transversely to the left from the position seen in Figure 17 of the drawings, the head 89 on the pin passes through the enlarged end 85 of the slot and in the upward movement of the lever the shank of the pin rides upwardly through the inclined portion of the slot 84 and into the horizontal closed end portion 86 thereof.

In Figure 18 I have shown another means for engaging the locking pin in the angular slot of the flange or plate. In this case the operating lever 16^a is formed in one piece and to the lever one end of a leaf spring 90

is fixed, said spring extending longitudinally along one side of the lever handle in opposed relation to a channel or recess 91 in the handle. The pin 92 fixed at one of its 5 ends to said spring is freely movable through an opening in the lever bar. When the handle is grasped to lift the lever to its locking position, the spring 90 is pressed into the groove of the handle and the pin 92 is thereby projected from one side of the lever bar 10 and into the slot 84. In this construction the slot 84 and the pin 92 are of the same form as shown in Figure 18 of the drawings.

In Figure 19, a manually operated means 15 for raising the latch operating lever to its locking position is shown. This means consists of a slide plate 94 having an inclined cam slot 95 the upper end of which is enlarged as at 96 to provide a seat for the pin 20 97 which is fixed in the upper end of the operating lever and engaged in said slot. The lower end of this slot 95 is open and slightly flared so that it will readily receive the pin when the slide is moved in one direction. 25 Such movement of the slide is resisted by a suitable spring 98 which operates to yieldingly hold said slide in its normal position. When the slide member 94 is moved to the right from the position shown in Figure 19, the cam slot 95 coaxing with the pin 97 will force the latch operating lever upwardly to its locking position until the pin 97 seats in the enlarged end 96 of said slot whereby the slide member is held in 30 such position and the spring 98 retained under tension. When the lever is to be moved downwardly to its operative position, such movement is started by exerting sufficient pressure against one side of the lever handle 35 to move the pin 97 from its seat 96 into the upper end of the slot 95. The spring 98 then acts to return the slide to its normal position, the camming action of said slide upon the pin 97 forcing the lever downwardly, in 40 which position the pin 97 is located at the open end of the slot 95. The lever may now be actuated to retract the latch bolt.

In Figures 20, 21, I have disclosed a key-actuated means operable from the exterior 50 of the car door for shifting the interior latch actuating lever. This means consists of a plate 99 pivotally mounted as at 100 upon the inner wall of the slot or channel in the door body in which the interior operating lever is movable. The plate 99 is provided in one side with an arcuate channel or groove 101 open at one of its ends and in which the pin or stud 102 on the latch operating lever is engaged. This plate also has 55 an arm 103 extending downwardly from its pivoted end. A key-actuated cylinder lock generally indicated at 104 is mounted in the door body above the exterior operating handle for the latch, the lock cylinder 60 having an arm 105 on its inner end which

is operatively connected by means of a bar 106 to the arm 103. Thus, as seen in Figure 20, the interior latch actuating lever mounted and arranged as shown in the several embodiments of the invention above referred to may be vertically shifted to lock 70 said lever as well as the exterior operating handle for the latch mechanism by means of a suitable key inserted into the lock 104 after the door has been closed. Upon turning the key in the proper direction, through 75 the connection 106, the plate 99 is shifted to the dotted line position. The walls of the arcuate cam groove 101 coaxing with the pin 102 will thus act to force the interior 80 operating lever upwardly to its effective locking position. A reverse movement of said plate by means of the locking key will, of course, move the lever downwardly so that the exterior operating handle may be actuated 85 to retract the latch bolt.

From the foregoing description considered in connection with the accompanying drawings, the construction, manner of operation and several advantages of the various embodiments of the invention herein disclosed will be clearly understood. In so far as I am aware, I am the first in the art to provide means controlled by a manipulation of the latch operating handle for rendering such 90 means effective to prevent the operation of the latch mechanism to retract the bolt, or on the other hand, to render such locking means ineffective in the event that independent means is provided for actuating the 95 locking means to prevent retraction of the bolt. It will be apparent that my present improvements particularly as illustrated in Figure 1 of the drawings, provides a much simpler and more easily operable locking 100 means for the latch mechanism than that disclosed in my issued Patent No. 1,386,492. The present improved construction has also been found to be very effective and reliable 105 in actual operation.

While I have herein shown and described several possible alternative forms of the generic invention involved in this application, it will nevertheless be understood that the device is also susceptible of still further 115 modifications and I therefore reserve the privilege of resorting to all such legitimate changes as may be fairly embodied within the spirit and scope of the invention as claimed.

I claim:

1. In a latch, a latch bolt, retracting means for said bolt including a manually operable member movable in a plane parallel with the operating plane of said bolt, 125 and means for locking the retracting means against operation by said member automatically controlled and rendered effective or ineffective by the manipulation of said member.

2. In a latch, a latch bolt, retracting means for said bolt including a manually operable member movable in a plane parallel with the operating plane of said bolt, and means for locking the retracting means against operation controlled by said member and rendered effective upon a movement of said member while the latch bolt is in projected position to thereby prevent the retraction of the latch bolt by the operation of said member.

3. In a latch, a latch bolt, retracting means for said bolt including independently operable members spaced from each other longitudinally of the bolt and each adapted to effect retraction of the bolt, and means rendered effective by a movement of one of said members to prevent retraction of the bolt by the actuation of either of said members.

4. In a latch, a latch bolt, retracting means for said bolt including independently operable members each adapted to effect retraction of the bolt, and means rendered effective by a movement of one of said members to prevent retraction of the bolt by the actuation of either of said members, said means being constructed and arranged to permit, when in its effective locking position, of the retraction movement of the bolt by pressure directly applied to one end of the bolt.

5. In a latch, a latch bolt, retracting means for said bolt including a pivotally mounted lever, and means for locking the retracting means against operation operatively controlled by said lever and effective in the projected position of the latch bolt to lock the bolt against retraction by the actuation of said lever.

6. In a latch, a latch bolt, retracting means for said bolt including a lever mounted for pivotal and rectilinear movement, and means for locking the retracting means against operation rendered effective by a rectilinear movement of said lever in the projected position of the bolt.

7. In a latch, a latch bolt, retracting means for said bolt including an operating member mounted for rectilinear movement in a plane parallel with the operating plane of said bolt, and means for locking the retracting means against operation automatically controlled and rendered effective by a rectilinear movement of said member when the bolt is in its projected position.

8. In a latch, a latch bolt, retracting means for said bolt including independently operable members, one of said members mounted for pivotal and rectilinear movement and each of said members adapted to effect retraction of the bolt, and means common to both of said members and rendered effective by a rectilinear movement of the

latter operating member to prevent retraction of the bolt from its projected position by the actuation of either of said members.

9. In a latch, a latch bolt, retracting means for said bolt including an operating member, and means carried by said member adapted to be engaged with a relatively fixed part to thereby prevent the actuation of said retracting means while permitting of the retraction movement of the bolt by pressure applied directly to one end of the bolt.

10. In a latch, a latch bolt, retracting means for said bolt including an operating member, an element connected to and movable with a part of the retracting means and means carried by said member and movable into the path of movement of said element to prevent the actuation of said retracting means.

11. In a latch for doors and the like, a latch bolt, retracting means for said bolt including members coacting respectively with parts spaced longitudinally of the bolt and independently operable from opposite sides of the door and each adapted to effect retraction of the bolt, and means controlled by the manipulation of the operating member on the inner side of the door to lock the retracting means against actuation by the operating member on the outer side of the door.

12. In a latch, a latch bolt, retracting means for said bolt including independently operable members spaced from each other longitudinally of the bolt and each adapted to effect retraction of the bolt, and a common locking means for said operating members including a part carried by one of said members and adapted to be positioned in the path of movement of a part of said retracting means to thereby prevent retraction of the bolt.

13. In a latch, a latch bolt, retracting means for said bolt including members spaced from each other longitudinally of the bolt and independently operable from opposite sides of the latch, and means for preventing the retraction of the bolt by the operation of either of said members including a part carried by one of said members adapted to be engaged with a fixed part and also disposed in the path of movement of a part of said retracting means.

14. In a latch, a latch bolt, retracting means for said bolt including a manually operable member, an element connected to and movable with a part of the retracting means and means associated with said member and adapted to be engaged with a fixed part and also disposed in the path of movement of said element to prevent the actuation of the retracting means.

15. In a latch, a latch bolt, retracting

means for said bolt, including a manually operable member, and means rendered effective by the manipulation of said member to lock the retracting means against operation by said member but permitting of the retraction movement of the bolt by pressure applied directly to one end of the bolt.

16. In a latch, a latch bolt, retracting means for said bolt, including a rectilinearly shiftable member movable in a plane parallel with the operating plane of said bolt, and means carried by said member adapted to coact with a part of the latch mechanism when said member is shifted in

one direction to lock the bolt against retraction.

17. In a latch for doors and the like, a latch bolt, retracting means for said bolt including interior and exterior independently operable members spaced from each other longitudinally of the bolt, and means for locking the bolt against retraction by the exterior operating member, including a part carried by the interior operating member. 20 25

In testimony that I claim the foregoing as my invention, I have signed my name hereunder.

LEON OTTINGER.
